UNITED STATES PATENT OFFICE.

WILLIAM D. ARNETT, OF SPRINGFIELD, OHIO.

SEEDING-MACHINE.

SPECIFICATION forming part of Letters Patent No. 416,542, dated December 3, 1889.

Application filed March 11, 1889. Serial No. 302,863. (No model.)

To all whom it may concern:

Be it known that I, WILLIAM D. ARNETT, of Springfield, in the county of Clark and State of Ohio, have invented certain Improvements in Seeding-Machines, of which the following is a specification.

This invention has reference more particularly to that class of machines in which the seed-receiving furrows are opened by means of upright disks attached to drag-bars in planes oblique to the lines of travel, although certain of the features are also applicable in other machines.

In the accompanying drawings, Figure 1 represents a perspective view of the forward portion of the main frame, looking upward against the under side, and illustrating more particularly the shaft and supports by which the drag-bars are carried. Fig. 2 is a side elevation of one of the drag-bars with the draft-connections to the main frame, one of the disks being removed to expose other parts to view. Fig. 3 is a longitudinal vertical central section through the drag-bar and its attachments. Fig. 4 is a vertical section on the line 2 2 of Fig. 2, looking rearward. Fig. 5 is a side view of one of the weighted rods for depressing the drag-bars. Fig. 6 is a horizontal section on the line 3 3 of Figs. 2 and 3. Fig. 7 is a perspective view of the plate at the forward end of the drag-bar. Fig. 8 is a side elevation on a reduced scale of my improved seeding-machine.

Referring to the drawings, A represents a rigid rectangular main frame, constructed of wood or other material in any suitable manner, and mounted, as usual, upon two ground-wheels B.

C represents a series of longitudinal drag-bars arranged side by side, as usual, the forward end of the series being mounted on a horizontal cross-shaft D, lying beneath the main frame. This shaft D is supported by vertical arms d d', &c., extending rigidly downward from a cross-bar d² of the main frame. It is also braced and stiffened by means of bars d³, extending upward to the forward part of the frame in a manner very similar to that in a patent heretofore granted to me.

To the shaft D, I connect by a strap e or

equivalent connections, a transverse draft-bar or evener E, to which I connect at the middle by a clevis e' or other suitable coupling, a doubletree F, which is in turn provided with singletrees for two, three, or more draft-animals side by side. Under this arrangement the power required to advance the machine is applied through the shaft D directly to the forward ends of the drag-bars, instead of being applied indirectly through the frame, as usual. This is advantageous, in that it admits of the parts being of lighter construction than would otherwise be admissible, and also in that it overcomes the tendency of the frame to tip downward at the front and throw an excessive weight on the necks of the draft-animals. The frame will be provided, as usual in machines of this class, with a central tongue or draft-pole 70 bolted rigidly thereto and extending forward, as shown at G.

An important feature of the present invention resides in the construction of the drag-bar and its attachments. Each bar consists, primarily, of an upper longitudinal strap or bar c and a lower strap or bar c', the two being applied at their forward ends to the upper and lower faces of the draft-head c² and bolted or riveted firmly thereto. The upper member c is straight, or substantially so, while the lower member is carried downward at the rear end and united to the upper member by a bolt or rivet.

The draft-head c² is made, as shown in Fig. 7, in the form of an open plate or ring flanged at the top and bottom to receive the parts c c', and provided at its ends with tubular trunnions or sleeves to receive the supporting-shaft D. These draft-plates afford widely-separated bearings for each drag-bar, so that its rear end is prevented from swaying laterally and bearing against each other at the sides. They maintain the proper separation of the drag-bars and prevent the same from sliding laterally on the shaft. Between the parts c c' of the drag-bar, near the rear end, is inserted a post or standard c³, having its ends flanged and secured to the parts c c' by vertical bolts, as shown. One face of this standard is provided with a series of teeth c⁴, as shown in Figs. 2, 3, and 4. To this toothed face is ap-

plied a vertically-adjustable block or casting c^5 , having at its two sides the journals or trunnions c^6 , to carry the respective furrow-opening disks. The plate c^5 is held to its place by a horizontal bolt c^7 , passing through the plate and a vertical seat in the standard to the back of the latter. This construction admits of the block c^5 and the disks being raised and lowered in relation to the under face or shoe of the runner in order to determine the depth of the furrow, the descent of the disks being limited by the shoe or runner, which rides upon the surface.

Over the top of the standard upon the upper surface of the part c is seated a plate c^9 , having an upright ear to carry the transverse pivot-bolt c^{10} , which supports the arms or ears of the two seed tubes or conductors H . These tubes, which are of oval or elliptical form in cross-section, are mounted one on each side of the drag-bar, their lower ends passing downward close to the inner faces of the respective disks in position to deliver seed into the furrow. It will be observed that the supporting arms or ears of the seed-tubes extend forward therefrom, and that they rest on top of the plate c^9 . This arrangement permits the lower end of each tube to tip backward and upward in the event of its encountering an obstruction, and gravitating to its original position as soon as it is set free.

In order to maintain the proper separation of the lower ends of the seed-tubes, I apply a wooden block I at the under side of the part c , and in position to bear against the inner sides of the conductors. This block may be secured in position by a vertical bolt i , which also serves to unite the standard and the part c . I commonly provide the standard with a central depending rib or lug c^{11} , which enters a slot in the top of the separating-block I , to keep the latter in its central position.

For the purpose of forcibly depressing the drag-bar and disks when operating on sod or unplowed land, I connect to the rear end of each tube, as in previous machines, a vertical rod J , which is provided with suitable weights. I now connect this rod to the drag-

bar in the peculiar manner shown in Fig. 50. The upper member c of the drag-bar has its rear extremity curved upward and then downward, provided with the perforation c^{12} , through which a link or ring c^{13} is inserted. The lower end of the rod J is fashioned into a hook, such as shown in Fig. 5. When the rod is in a horizontal position, this hook may be inserted through the link, as shown; but on turning the rod to its upright or operative position its detachment becomes impossible.

Having thus described my invention, what I claim is—

1. In combination with the sustaining-shaft and the series of drag-bars, the series of draft-heads, each having the sleeves mounted on the shaft, and the flanged faces bolted to the drag-bars.

2. The draft-head for a seeder drag-bar, consisting of the open plate provided with the sleeves and with the flanged surfaces to receive the drag-bar.

3. In combination with the upper and lower members of the drag-bar, the intermediate standard, the block provided with the disk-sustaining axles and applied to the standard, and the clamping-bolt uniting the block and standard, substantially as shown.

4. In combination with the drag-bar and the furrow-opening disks carried thereby, the hinged gravitating conductor-tubes and the intermediate spreading-block attached to the drag-bar.

5. In a seeder or kindred machine, the combination of the wheeled main frame, the cross-shaft rigidly supported thereunder, the drag-bars jointed directly to said shaft, and the draft-bars also connected directly to the shaft, whereby the draft is transmitted directly to the drag-bars instead of being transmitted through the frame, as usual.

In testimony whereof I hereunto set my hand, this 16th day of February, 1888, in the presence of two attesting witnesses.

WILLIAM D. ARNETT.
